Attorney

UNITED STATES PATENT OFFICE.

FRED BECKER, OF BUFFALO, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed July 30, 1921. Serial No. 488,538.

To all whom it may concern:

Be it known that I, FRED BECKER, a citizen of the Republic of Switzerland, residing in Buffalo, in the county of Erie and State of New York, have invented certain new and useful Improvements in Typewriting Machines, of which the following is a specification.

This invention relates to means to facilitate the adjustment of work-sheets or cards on the platens of combined typewriting and computing machines, and is in the nature of an improvement on the invention disclosed in the application of Charles M. Hilsee, Serial No. 453,079, filed March 17, 1921.

In certain classes of work, entries are made in different divisions of work-sheets or cards, said divisions being arranged in rows both transversely and longitudinally of the work-sheets. Furthermore, in many cases, entries are to be made in succession in corresponding divisions on a plurality of such work-sheets or cards necessitating the rapid removal of one work-sheet and the insertion of another.

As herein disclosed, the work-sheet is in the form of a card for use as a record or ledger-sheet for monthly entries and is divided into three main columns, each of which is divided into secondary columns. These secondary columns have headings to indicate "Old bal," "Credit," "New bal" and "Date."

When the machine is set for the typing of entries in one of the main columns and for effecting computations therein, and it is desired to write in another of the main columns and effect computations in said column, it is desirable to avoid the resetting of the denomination-controlling mechanism and of the tabulating stops, since this requires considerable time. It is desirable also that means be provided for expediting the accurate positioning of the cards in the machine both longitudinally and laterally to receive entries in desired locations.

To this end, provision is made of a front paper-table having a side gage and an adjustable leading-edge gage, said paper-table being adjustable laterally of the machine to bring its side-edge gage into position to locate the work-cards with any one of their main columns in co-operative alignment with the computing and tabulating mecha-

nisms. As herein disclosed, a bar, having 55 teeth at letter-space distances at its upper edge, is supported above the platen, and the front paper-table is provided with spring-clips, so that, when placed on the bar, it will be yieldingly retained thereon, provision being made of a suitable member on the paper-table to co-operate with the teeth to insure proper positioning of the paper-table and to prevent longitudinal movement thereof relative to the bar. 60

A feature of the invention is the provision of improved means for facilitating the adjustment of the leading-edge gage with reference to the front paper-table.

Another feature of the invention is the 70 provision of an improved clip to hold a card on the front paper-table.

Other features and advantages will hereinafter appear.

In the accompanying drawings, 75

Figure 1 is a fragmentary perspective view, showing my invention as applied to the platen-frame of an Underwood typewriting machine.

Figure 2 is a side view of substantially the 80 same parts as shown in Figure 1.

Figure 3 is a fragmentary perspective view of the novel structure viewed from the rear.

Figure 4 is a view showing one form of 85 work-sheet used in connection with the invention.

Figure 5 is a detail sectional view, showing the clip and the manner of supporting the same on the front paper-table. 90

Figure 6 is a detail view, partly in section, showing a modified form of the means by which the leading-edge gage is held in adjusted position on the front paper-table.

The combined typewriting and computing 95 machine, which may be a bookkeeping machine of the Underwood-Hanson type, comprises a platen 11 supported by an axle 12 journaled in the ends 13 of the platen-frame. Mounted on a rod 14, supported by the ends 100 13 of the platen-frame, are plates 15 and 16 normally held against rotation on rod 14 by means of a rod 17 lying in notches 18 and 19 in the plates 15 and 16, respectively, and supported at its ends in brackets 20 carried 105 by the ends 13 of the platen-frame.

Lugs 21 at the forward edges of plates 15 and 16 serve to support a bar 22 extending

longitudinally of the platen, the connection between the bar 22 and the lugs being made by screws 23 extending through slots 24 in the ends of said bar 22, and threaded into the lugs 21. It will be seen that the provision of the slots 24, which extend transversely with respect to the bar, enables the adjustment of the latter at different heights above the platen. Preferably, the lugs 21 extend in the same direction from plates 15 and 16, and the plates are duplicates.

The bar 22 is provided on its upper edge with teeth 25 at letter-space distances to receive in the notches therebetween a tooth 26 on a block 27 secured by screws 28 to the plate 29 of the front paper-table 30. The front paper-table may be secured to the bar 22 by means of spring-clip devices 31 near each side of the paper-table. Each 20 of the devices 31 includes a spacer 32, a leaf-spring 33 having a latching projection 34, a spring or supporting member 35 overlying a portion of the leaf-spring 33, and a screw 36 maintaining these parts in position. It 25 will be seen that each of the projections 34 may consist of a beveled pin fixed in the end of the spring 33, or the projection may be formed by pressing a portion of the metal of the spring to one side.

30 The front paper-table 30 also includes a plate 37 secured to the lower part of the plate 29, and, as shown in Figure 1, the plate 37 is beveled at 38 to enable the use of the adjacent edge of the plate 29 in connection with letter-space graduations 39 on the bar 22 in positioning the paper-table along the bar 22. It will be seen that the paper-table 30 may readily be brought to any one of the line-space positions, indicated 35 by the graduations 39, on the bar 22. After the paper-table has been brought to the desired letter-space position, it may be secured on the bar 22 by a downward movement. In this movement the leaf-springs 33 will 40 be cammed outwardly by a cam-surface 40 formed by beveling the rear face of the bar 22, and, upon completion of the downward movement, the projections 34 will snap under the lower edge of the bar 22, as indicated in Figure 2, and the paper-table will 45 be held firmly in position. However, when it is desired to shift the paper-table 30 to another position, it may be detached from the bar 22 merely by lifting, since the 50 tapered projections on the leaf-springs 33 will, when sufficient pressure is exerted, ride over the lower rear edge of the bar 22 and permit the paper-table to be withdrawn from the bar. It will be evident that, when 55 the paper-table 30 is lifted to withdraw the tooth 26 from engagement with the teeth 25, it may be shifted longitudinally along the bar 22 without being withdrawn therefrom.

60 A portion of the plate 29 extends above the plate 37, and is provided at its sides

with rearwardly-extending flanges 41, having perforations 42 at line-space distances therealong. The front face of the extension is also provided with line-space graduations 43 indicating the positions of the perforations in the flanges. Extending across the front of the extension is a bar 44, having at its upper edge a flange 45, which may be used as a leading-edge gage. Adjacent the flanges 41, the bar 44 is provided with blocks 46, having slots 47 therein, to receive said flanges 41, the blocks 46 being secured to the rear face of the bar 44 in any suitable manner, as, for example, by brazing. The bar 44 may be secured in any of the positions to which it is adjusted, by means of the graduations 43, by screws 48 threaded into the blocks 46 and extending across the slots 47 when turned by the knurled ends 49 to move them through the correspondingly-positioned perforations 42.

65 The paper-table 30 is provided with a left-hand edge-gage 50, preferably formed by bending the plate 29 around the left-hand end of the plate 37 so as to extend at right-angles to the outer face of the plate 37. Provision may also be made of means to hold a work-sheet or card in position on the paper-table 30. For this purpose, use is made of a bracket 51, secured to the rear face of the plate 29, passing around the edge gage 50, and extending to the right substantially parallel to the front face of the paper-table. Secured near its middle to the free end of the bracket 51 is a spring 52, the two 70 branches 53 of which extend towards the front face of the paper-table so as to press thereagainst, and are bent outwardly at their ends. The connection between the spring 52 and the bracket 51 may be effected 75 by any suitable means, such as a screw 54. It will be evident that the spring 52 will be particularly effective in holding a card or work-sheet in position on the paper-table, due to the fact that it engages the latter 80 at two points at a substantial distance apart.

85 The card 55, which is herein disclosed as the card to be used, is provided, below the heading, with three major columns, each of which is divided into three minor columns, designated in order, from left to right, as "Old bal," "Credit," "New bal," and "Date." Provision is also made of transverse lines. One of these cards is used with each individual account, and is used as follows: At 90 the end of January of the first year provided for, the card is inserted into the machine, the paper-table being positioned at the right-hand end of the carriage, and any previous balance which may exist is typed in the first minor column, and in the upper line thereof; the carriage is moved to the left, and the amount of any transaction 95 during the month typed in the second minor column. The new balance is then computed 100

and entered in the next column and in the same line, and, if the name of the month, January, does not appear in the date column, it should be typed in that position.

- 8 Other cards, on which entries are to be made for January, are picked up, one by one, placed in the machine, and the proper entries made in the first line and in the first major column, the position of the entries 10 corresponding to January. Each card, when the entries have been typed thereon, is removed from the machine, and the next card placed therein. At the end of the second month, entries will be made in a corresponding 15 manner in the first line in the second column, which corresponds to February; and, at the end of the third month, in the same line, but in the third major column, the March entries will be made. It will be 20 evident that for the first three months the front paper-table is set in a different position for each month, and that the leading-edge gage 45 is secured on the paper-table so as to position the upper line of the card 25 at the printing line. After the entries for the first three months have been made, the paper-table 30 is again shifted to its right-hand position, and the bar 44, carrying the leading-edge gage, is secured thereon in a 30 position one line-space higher than before.

It will be seen that cards having different numbers of major columns may be used, in accordance with the requirements of the work, but, in using the sheet or card 35 closed, the procedure is substantially as follows: The letter-space position of the front paper-table 30 and the line-space position of the bar 44 are determined in advance for typing on the cards 55. In starting entries 40 on a card, therefore, the paper-table is positioned at the proper letter-space position by means of the right-hand edge of the plate 29 adjacent the beveled portion 38 of the plate 37, the edge of the plate 37 being 45 used in connection with the graduations 39 on the bar 22 and the bar 44 being set at the proper line-space position by means of the screws 48 and the perforations 42. After 50 the paper-table has been brought to the correct letter-space position along the bar 22, it is shoved downwardly thereon, and the leaf-springs 33 are pressed outwardly by the inclined surface of beveled portion 38 and then permitted to snap into position, with 55 the projections 34 lying beneath the lower edge of the bar 22. The bar 44 is also set on the paper-table with the leading-edge gage 45 in the proper position.

The card to be typed upon is then 60 inserted at either the rear or front of the platen, while the feed-rolls 56 are cast off, and swung laterally beneath the upturned ends of the portions of branches 53 of the spring 52, the card being gaged at the left-hand edge by the edge-gage 50. Assistance

in such edge-gaging may also be furnished by means of a side-gage 57 on the left-hand end of bar 44, the forward edge of the card being gaged by the flange 45. Typing may then be effected by means of types 58 on 70 type-bars 59. The feed-rolls may be moved to effective position to hold the card during such typing, or may be left in cast-off position, the pressure of the spring 52 being sufficient to maintain the card in position 75 on the front paper-table during such typing. When entries are to be made for a succeeding month, the front paper-table 30 may be lifted to release it from the bar 22 and shifted to the proper position for 80 typing in another major column, the bar 44 being adjusted, if necessary, to the proper line-space position.

In the modified form of leading-edge-gage-retaining device shown in Figure 6, a 85 pin 60, slideable in a block 46, is urged inwardly to engage in one of the perforations 42 by means of a spring 61, extending into a slot 62 in an enlarged portion 63 of the pin 60. The pins 60 may be withdrawn 90 from the perforations 42, and the bar shifted slightly to one side, so that the pins 60 will rest on the outer faces of the flanges 41 and, when the bar is brought to proper position, the springs 61 will cause the pins 95 60 to enter the next pair of perforations. The withdrawal of the pins may be effected by knurled heads 64 on the pins 60.

It will be evident that the arrangement, 100 by which the adjustment of the paper-table 30 along the bar 22 is determined by a tooth 26 on the paper-table and a plurality of teeth 25 at letter-space distances along the bar make it possible to position the paper-table for cards having different arrangements of columns corresponding to the major columns in the present case.

Variations may be resorted to within the scope of the invention, and portions of the improvements may be used without others. 110

Having thus described my invention, I claim:

1. In a machine having writing and computing mechanisms, in combination, a platen, a platen-frame, a bar on said platen-frame above the platen, said bar having a series of teeth on its upper edge, a front paper-table having a tooth on its back, said teeth on the bar and paper-table co-operating to determine and maintain the exact lateral position of the paper-table in the machine to enable the paper-table to position the work properly with relation to the computing mechanism, said paper-table normally being positioned against the front face of the bar, and means including spring-clips to yieldably hold the paper-table against removal from the bar. 120

2. In a machine having typewriting and computing mechanisms, in combination, a 130

platen, a platen-frame, a front paper-table, a bar above the platen supporting the paper-table, having a front face to be engaged by the rear face of the paper-table, said bar and paper-table being relatively adjustable to enable the paper-table to position the work properly with relation to the computing mechanism, and comprising interfitting elements to determine and maintain different adjustments of the bar and paper-table, and means including a spring-clip to yieldably hold the paper-table against removal from the bar.

3. In a typewriting and computing machine, in combination, a platen, a platen-frame, a bar on said platen-frame above the platen and having notches in its upper edge, a front paper-table having means on its back to co-operate with said notches when placed against the front face of the bar, and spring-latching means to yieldably hold the paper-table on the bar when placed with its back against the front face of the bar and moved downwardly to cause the means on the back of the paper-table to co-operate with said notches.

4. In a typewriting and computing machine, in combination, a platen, a platen-frame, a bar above the platen beveled at the rear to make it thinner at its upper edge, a front paper-table, provision on said bar and paper-table whereby, when said paper-table is placed against the front face of the bar and moved downwardly, it will be held against movement longitudinally of the bar, and spring-detents on said paper-table movable therefrom by the beveled portion of said bar, so that they may snap into effective position below the lower edge of the bar when the positioning of the paper-table is completed.

5. In a typewriting and computing machine, in combination, a platen, a platen-frame, a bar above the platen beveled at its rear to make it thinner at its upper edge, said bar being provided, with teeth at its upper edge, a paper-table, a projection on the rear of said paper-table to engage said teeth, and leaf-springs on the rear face of said paper-table at each side thereof having forwardly-extending projections at their lower ends whereby, upon placing the paper-table on the front face of the bar and moving it downwardly to pass the projection on the back thereof between two of said teeth, the springs will be cammed outwardly and then released to permit the projections thereon to snap into position beneath the lower edge of said bar.

6. In a typewriting and computing machine, in combination, a platen, a platen-frame, a front paper-table, a support for said paper-table mounted on the platen-frame, means on said support and paper-table for holding the latter against move-

ment longitudinally of the former in any one of a plurality of letter-space positions thereon, and means for yieldingly opposing separation of the support and paper-table in any one of said letter-space positions.

7. In a typewriting and computing machine, in combination, a platen, a platen-frame, a front paper-table, a bar on the platen-frame above the platen and extending in the direction thereof, having a front face to be engaged by the rear face of said paper-table, and means including a spring-detent device for holding the paper-table in different letter-space positions on the bar, and for yieldingly resisting removal of the table from the bar.

8. In a typewriting and computing machine, in combination, a platen, a platen-frame, a bar on said platen-frame above the platen, said bar having a series of teeth on its upper edge, each tooth being of letter-space extent, and a set of letter-space graduations on its front face, a front paper-table having a tooth on its back to co-operate with the teeth on said bar in determining the exact position of the table, and having a straight-edge portion to co-operate with said graduations in positioning the paper-table, and spring-clip means to hold said front paper-table in position against the front face of the bar.

9. In a typewriting machine, in combination, a platen, a platen-frame, a front paper-table mounted on the platen-frame and extending above the platen, said paper-table having rearwardly-extending flanges, a leading-edge gage-device comprising a bar resting on the face of the paper-table, members secured to the bar near its ends, and provided with slots to receive the flanges, and means to hold said members in position on said flanges when the gage-device has been brought to adjusted position.

10. In a typewriting machine, in combination, a platen, a platen-frame, a front paper-table mounted on the platen-frame and extending above the platen, said paper-table having rearwardly-extending flanges, a leading-edge gage-device comprising a bar resting on the face of the paper-table, members secured to the bar near its ends, and provided with slots to receive the flanges, and means effective only at line-space intervals to secure said gage-device in position on the paper-table.

11. In a typewriting machine, in combination, a platen, a platen-frame, a front paper-table mounted on the platen-frame and extending above the platen, said paper-table having rearwardly-extending flanges, provided with perforations at letter-space distances, and a leading-edge gage-device comprising a bar resting on the face of the paper-table, members secured to the bar near its ends, and provided with slots to receive

the flanges, and spring-pressed pins in said members to enter the perforations in said flanges when moved into register therewith.

12. In a typewriting machine, in combination, a platen, a platen-frame, a front paper-table mounted on the platen-frame above the platen, said paper-table having recesses at line-space distances along each edge, and a leading-edge gage-device comprising a bar extending across the face of the paper-table, members shaped to fit around the paper-table at its edges, secured to said bar and serving to hold the latter on the paper-table, and spring-detent devices to co-operate with said recesses when the gage-device is moved to corresponding line-space positions.

13. In a typewriting and computing machine, in combination, a platen and a sheet-holding device whereby a work-sheet may be positioned and held in position during typing thereon, said device comprising a front paper-table having leading-edge and side-edge gages, an arm extending inwardly over the side-edge gage on one side of the paper-table, and a leaf-spring secured near its middle to said arm and pressing against the paper-table at each side of the point of connection with the arm, the ends of the spring being upturned so as to facilitate the insertion of work-sheets thereunder.

14. In a typewriting and computing machine, in combination, a traveling carriage, a revoluble platen therein, a support on said carriage extending across the same above the platen, a front paper-table having a leading-edge gage, a side-edge gage and a yielding device to hold on the paper-table a work-sheet of width within the capacity of the machine, provisions on said support and paper-table whereby the paper-table may be adjusted to any one of a plurality of letter-space positions along the support, so that any column on the sheet may be placed over a given field on the platen, irrespective of the size or number of the columns, and yieldable holding means adapted to hold the paper-table in position when the latter is grasped by the operator and placed on the support, and to yield and permit the removal of the paper-table when the latter is grasped by the operator and withdrawn from said support.

15. In a typewriting and computing machine, in combination, a platen and work-sheet-controlling means whereby a work-sheet may be positioned and held for typing in different columns thereon when these columns are placed over a given field of the platen, said means comprising a front paper-table having leading-edge and side-edge gages, and yielding means to press the work-sheet against the platen at two separated points, a paper-table support, provisions on said paper-table and support to

permit the former to be set on the latter at a plurality of letter-space positions, and yieldable holding means for the paper-table rendered effective by placing the paper-table on said support in any one of said letter-space positions and adapted to yield when the paper-table is grasped by the operator and withdrawn from said support.

16. In a machine having writing and computing mechanisms, a front paper-table having a side gage thereon, the paper-table being adjustable laterally for positioning cards in the machine in selected locations to locate them in co-operative relationship to the computing mechanism, an arm extending from the side gage across the paper-table, and a bow-spring secured intermediate its ends to said arm and having its opposite ends directed toward the paper-table to engage the work thereon and press it against the paper-table.

17. In a machine having writing and computing mechanisms, a front paper-table having a side gage thereon, the paper-table being adjustable laterally for positioning cards in the machine in selected lateral locations to correctly locate them with reference to the computing mechanism, a leading-edge gage adjustably mounted on the paper-table, an arm extending across the paper-table from one side thereof, and a bow-spring connected intermediate its ends to said arm for pressing the work toward the paper-table at spaced points.

18. In a typewriting machine, a front paper-table for positioning cards in the machine, an arm extending above the paper-table, and a bow-spring connected intermediate its ends to said arm and having its ends directed toward the paper-table to engage the work thereon at points spaced laterally from each other.

19. In a typewriting machine, a paper-table, a bow-spring positioned above said table, and means supporting the bow-spring intermediate its ends in a position to cause its ends to bear against the work positioned on the table.

20. In a bookkeeping machine having writing mechanism including a platen traveling transversely of the machine and computing mechanism settable to determine successive computing zones on the platen, the combination with the platen, of a front paper-table with a side gage to position on the platen a work-sheet having a plurality of major columns, each comprising minor columns corresponding to said computing zones, and means for locating said front paper-table at mechanically-determined letter-space intervals from one end of the platen to the other to bring any one of said major columns into alignment with a zone on the platen, comprising minor computing zones, corresponding to the minor columns

of a major column on the work-sheet, obtained by setting the computing mechanism to determine such zones at any desired position along the platen to enable computation **5** to be effected concomitantly with the typing of any one of said minor columns.

21. In a typewriting machine, the combination with a front paper-table, of a leading-edge gage therefor, a support on which **10** said gage is mounted to slide to and from the printing line and provided with open-

ings at line-space intervals, and means to detain the leading-edge gage at any one of the positions corresponding to said openings, comprising a spring-pressed member **15** to fit into said openings when brought into register therewith.

FRED BECKER.
